Primary Examiner — Calvin E Vansant**CLAIM**

The ornamental design for a self balancing electric unicycle, as shown and described.

DESCRIPTION

FIG. 1 is a top, front and left side perspective view of a self balancing electric unicycle showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings illustrate portions of the self balancing electric unicycle which form no part of the claimed design.
